UNITED STATES PATENT OFFICE.

HENRY CAMPBELL, OF LOGAN, UTAH.

ORE-SEPARATOR.

1,368,111.

Specification of Letters Patent.

Patented Feb. 8, 1921.

Application filed June 30, 1920. Serial No. 393,078.

To all whom it may concern:

Be it known that I, Dr. HENRY CAMPBELL, a citizen of the United States, residing at Logan, in the county of Cache and State of Utah, have invented a new and useful Ore-Separator, of which the following is a specification.

This invention relates to an ore separator and has for an object the provision of means 10 for separating fine gold from fine sand, and a particular object of this invention is to provide means for separating particles of gold of the same atomical weights as that of sand from the sand.

15 Another object of this invention is the provision of means for economically separating flour gold from sand in indefinite quantities without the loss of the initial chemicals employed in the separation.

20 A further object of this invention is to provide an ore separator of generally improved constructions whereby the device will be simple, durable, and inexpensive in construction and maintenance, as well as 25 convenient, practical, serviceable, and efficient in its use.

With the above and other objects in view which will appear as the description proceeds, the invention resides in the combination 30 and arrangement of parts and in the details of construction hereinafter described and claimed, it being understood that within the scope of what is claimed, changes in the precise embodiment of the invention 35 shown can be made without departing from the spirit of the invention.

The invention has been illustrated in its preferred embodiments in the accompanying drawings, wherein:

40 Figure 1 is a side elevation of the device, parts appearing in section;

Fig. 2 is an enlarged plan view of a portion of the conveyer;

Fig. 3 is a fragmental longitudinal sectional view taken through the conveyer;

Fig. 4 is a transverse sectional view taken through the conveyer;

Fig. 5 is a fragmental detail view showing the hinged connection between the links 50 of the conveyer.

Referring to the drawings there is shown one form of my invention, which includes a frame or supporting structure 10, having spaced uprights 11, and a vat or tank 12 is 55 supported by the frame 10. Rollers or drums 13 and 14 are journaled on the stand-

ards 11, and a guide roller 15 is positioned within the tank 12 and is journaled on a standard or bearing 16.

An endless composite belt or conveyer 17 60 is trained around the rollers 13, 14 and 15, and this conveyer is composed of separate links 18. Each link comprises a body preferably formed of copper, and each body member has a recess or receptacle 19 formed 65 therein. A cover or housing plate 20 is secured to one face of the body member or link 19, and a transversely extending elongated slot 21 is formed in the plate 20. The intermediate portion of the plate is thickened to 70 provide an inclined face 22 which forms one wall of the slot 21, and co-operates with an inclined end wall 23 of the recess 19 to define a restricted outlet or neck 24. Side members or flanges 25 are secured to the 75 body member 19 at the opposed longitudinal edges thereof thereby defining a trough like structure. The links 19 are hinged to each other by means of bolts, or other securing devices 26, which pass through spaced attaching ears 27 projecting longitudinally from one end of a link and through an attaching lug 29 extending from the opposed end of the adjacent link. Each link or body member 19 has a concaved face 28 80 which is adapted to engage and conform to the periphery of the driving and supporting rollers, thereby presenting a flexible and efficient conveyer.

The discharge end of the sand chute or 90 sluice S overhangs the rollers 13 and a portion of the conveyer trough 17, so that the sand and water discharged from the sluice will flow over the conveyer 17, thereby permitting this conveyer to form in effect a 95 part of the sluice. A return trough 31 is supported by the frame and underlies the roller 13 and the lower run of the conveyer 17.

Any suitable means may be employed for 100 driving the device, and to this end a drive pulley 32 is secured to the roller 13 and is adapted to rotate therewith, and this pulley may be driven by a belt 33, which, in turn, may be driven from any suitable source of 105 power, not shown.

In operation, mercury M is supported at the bottom of the tank 12 and a suitable acid A is supported above the mercury. Power is now applied to the conveyer 17, and it is 110 driven in the direction indicated by the arrow, which direction is opposed to the di-

rection of flow of the water and sand from the sluice S. As the conveyer passes through the tank 12 the recesses or receptacles 19 are filled with mercury, and the acid 5 acts on any traces of iron that may collect on the links of the conveyer. As the links of the conveyer leave the tank 12 they will retain a full supply of mercury, owing to the shape of the recesses or receptacles 19, 10 and after these links have passed around the roller 14 the slight inclination of the conveyer will cause the mercury in each link to seek the level of the face of the conveyer, thereby disposing the mercury in the path 15 of the gravitating "pay-sand" and water. As the sand passes over the mercury riffles, the mercury will amalgamate with the gold that may be present, and then gold and mercury are conveyed over the roller 13 and 20 deposited into the return trough 31, which conveys them to the tank 12. The sand and water flows over the trough-like conveyer 17 and is discharged over the roller 14. After the amalgam of gold and mercury is 25 conveyed to the tank 12, they are drawn from the tank and separated, by distillation or any preferred manner, and then the mercury is returned to the tank for further use.

When the links 18 of the conveyer 17 are 30 traveling from the roller 14 to the roller 13, these links are slightly inclined and so disposed that their transversely disposed slots 21 are slightly below the common level of the mercury in the recesses or receptacles 19, 35 therefore the mercury by capillary elevation presents a convex surface above the upper edges of the slots 21, thereby providing effective riffles. The relatively great number of the riffles that this arrangement affords, 40 prevents the loss of any gold and provides means for collecting gold particles having the same atomical weight as sand. It is to be understood that the conveyer may be in the form of a wheel instead of a link conveyer, and in this way the wheel would be 45 provided with a number of recesses to carry the mercury present in the path of flow of the pay sands.

Having thus described my invention what 50 is claimed is:—

1. A device of the class described including a supporting frame, a tank supported by the frame, an endless conveyer operably

supported by the supporting frame, said conveyer comprising separate links which 55 are hingedly united, each link having a receptacle formed therein and a restricted neck leading from the receptacle to the operable face of the link, means for filling the said receptacles with mercury, and 60 means for driving the conveyer in a direction contrary to the direction of flow of the sands from the sluice in order to expose the mercury in the path of travel of the suspended sands. 65

2. A device of the class described including a supporting frame, a tank supported by the frame, rollers journaled to the frame, an endless conveyer supported by the rollers and adapted to be placed adjacent a sluice, 70 said conveyer comprising separate links which are hingedly united, each link having a receptacle formed therein and a restricted neck leading from the receptacle to the operable face of the link, means for filling the 75 said receptacles with mercury, and means for driving the conveyer in a direction contrary to direction of flow of the sands from the sluice in order to expose the mercury to the path of travel of the suspended sands. 80

3. A device of the class described including a supporting frame, a tank supported by the frame and adapted to contain mercury and acid, spaced standards supported by the frame, rollers journaled on the standards, 85 an endless conveyer trained over the rollers and passing through the tank and positioned adjacent a sluice, means for conveying the mercury from the tank and exposing it in the form of riffles in the path of flow of the 90 sands discharged from the sluice, a trough underlying the conveyer and leading to the tank and adapted to return the amalgamated mercury to the tank after it has been discharged from the conveyer, and means for 95 driving the conveyer in a direction opposite to the direction of flow of the sand from the sluice.

In testimony that I claim the foregoing as my own, I have hereto affixed my signature 100 in the presence of two witnesses.
